UNITED STATES PATENT OFFICE.

FREDERICK A. GUILLETTE, OF TAUNTON, MASSACHUSETTS.

SHOESTRING-FASTENER.

1,249,949.

Specification of Letters Patent. Patented Dec. 11, 1917.

Application filed September 24, 1915. Serial No. 52,479.

To all whom it may concern:

Be it known that I, FREDERICK A. GUILLETTE, a citizen of the United States, residing at Taunton, in the county of Bristol and 5 State of Massachusetts, have invented new and useful Improvements in Shoestring-Fasteners, of which the following is a specification.

This invention relates to shoe string fasteners and the principal object of the invention is to provide simple and efficient means 10 for connecting the ends of a shoe string in order to obviate the necessity of tying the same and to provide a more secure method 15 of holding the terminals of the string.

Further objects of the invention will appear as the following specific description is read in connection with the accompanying drawing, and in which:

20 Figure 1 is a side elevation of a shoe showing one method of lacing the same with the improved fastener applied thereto.

Fig. 2 shows a perspective view of the fastener removed.

25 Fig. 3 is a sectional view taken through the fastener while applied to the shoe.

Fig. 4 is a side elevation of a slightly modified form.

In the type of shoe shown in the drawings, the upper 1 is cut in the form of a button shoe and the marginal edges are provided with lacing hooks 2 to which the lace 3 is applied in the usual manner.

30 Adjacent the upper portion of the upper there is secured thereto a spring finger 4 having attached to its free terminal a substantially semi-spherical head 5 upon the upper portion of which is formed or attached a rearwardly extending flange or lip, 35 the purpose of which will be hereinafter described.

In Figs. 1, 2 and 3, the spring finger is attached to an eye member 7 and the ball head is arranged to fit a second eye member 8 coupled thereto by a bar 9. In Fig. 4, 40 the same type of head as is shown in Figs. 1 to 3 is employed but in this instance, the head is attached to the upper arm 11 of a U-shaped spring member the lower arm 12

of which has punched therefrom the hollow rivets 13 similar to the rivets 14 employed in connecting the device shown in Figs. 1 to 4 to the upper.

In attaching the terminal end of the string or lace to the device the lace is passed 50 under the head around the same, between the finger and the overhanging flange and is tightly pulled so as to carry the loop of the string beneath the ball head, thereby forming a half hitch around the finger which 55 is held against slipping by reason of the tension on the lace pulling the confined part of the lace against the head. A quick pull of the terminal end of the lace in the opposite direction will release it from the head. 60

65 What is claimed is:

1. A shoe lace fastener comprising a pair of connected hollow rivets, a spring arm secured to one of the rivets and projecting toward the other rivet, a semi-spherical head mounted upon the free terminal of the spring arm and held in engagement with the other rivet by said arm, and a rearwardly extending lip or flange on the head forming 70 a lace receiving channel between the head and arm. 75

2. As a new article of manufacture, a shoe lace fastener embodying a bar, a pair of hollow rivets carried at the opposite ends of said bar, a spring arm integrally formed 80 at one end of the bar and projecting toward the opposite or free end thereof, a semi-spherical head mounted on the free terminal of the spring arm and held in frictional engagement with the other rivet by the influence of said arm, and a rearwardly extending lip on the outer marginal edge of the head and disposed in spaced relation with respect to said arm, forming a lace receiving 85 channel between the confronting faces 90 of said lip and arm, substantially as and for the purpose specified. 90

In testimony whereof I affix my signature in presence of two witnesses.

FREDERICK A. GUILLETTE.
